VALVE

Aaron M. Edwards, Skellytown, Tex.

Application May 28, 1941, Serial No. 395,522

4 Claims. (Cl. 251—118)

This invention relates to a novel valve. In its more specific aspect the invention is directed to a novel check and relief valve finding particular application in the oil producing and refining fields.

Heretofore it has been the practice to employ compressed air for starting certain types of combustion engines. In the oil producing and refining fields large fires and loss of life has sometimes occurred by backfiring of the engines. In order to eliminate these dangers caused by backfiring, I have provided the present novel device. Moreover, I have provided a novel check and relief valve which has few parts and is sturdy; it can be readily dismantled and repaired without the necessity of removing it from the line; it is relatively inexpensive to manufacture, and is fool-proof.

These and other advantages of the invention will be readily apparent from the following detailed description and appended drawings wherein:

Figure 1 represents a side view of the combination embodying the invention.

Figure 2 is a vertical cross sectional view of the novel valve and is taken on line II—II of Figure 3 in the direction of the arrows.

Figure 3 is a top plan view of the novel valve shown in Figure 2.

Figure 4 is a horizontal cross sectional view taken on line IV—IV of Figure 2 in the direction of the arrows.

Figure 5 illustrates the different parts which make up the valve assembly.

Figure 6 is a fragmentary cross sectional view illustrating the relative position of parts during the passage of compressed air through the valve to the engine.

Figure 7 is a fragmentary cross sectional view taken on line VII—VII of Figure 6.

Figure 8 is a fragmentary cross sectional view, similar to Figure 6 and illustrates the relative position of parts during back-fire.

Figure 9 is a fragmentary cross sectional view, similar to Figure 7, and taken on line IX—IX of Figure 8.

In the field of producing petroleum oil there may be used an internal combustion engine 10 of the Diesel, Bessemer, Hopes, Cooper Bessemer, Clark, Miller, Worthington or other type which employs gas or oil as the source of energy and which generally is started by the use of compressed air. The compressed air employed for starting may travel from a tank (not shown) of compressed air to the engine 10 through a pipe

line 11, part of which may be underground. A control valve 12 may be located in that portion of the pipe line 11 which is above the ground and near the engine.

According to my invention, a check relief valve may be placed in the pipe line 11 at a position near the engine 10, and between the engine 10 and valve 12 above the ground. As shown, the novel valve comprises a hollow cylindrical body 13 preferably of hard steel. This body 13 may be of any desired practical dimensions and its length may be approximately twice its diameter. Both the upper and lower portions of body 13 are interiorly threaded at 14 and 15 respectively. At about the mid-length of said body 13, there is an opening which may be interiorly threaded and a relatively short coupling pipe or conduit 16, having an exteriorly threaded portion at one end may make threaded engagement therewith and its inner end may be approximately flush with the inner surface of the body 13. At about the quarter length of said body 13, lower than the mid-length opening and being about 80° from the mid-length opening is another opening in said body 13. This opening may also be interiorly threaded to accommodate the exteriorly threaded end of a pipe or conduit 17. Both pipes or conduits 16 and 17 may be of any desired practical dimensions, but I prefer that they be relatively short connections whose outer ends are interiorly threaded and may be readily inserted in a compressed air line.

An insert sleeve 18 is located in and secured to the hollow cylinder 13. The sleeve 18 comprises a hollow cylinder 19 having integral therewith an outwardly extending flange 20 whose external diameter approximates that of the cylinder 13. The upper portion of the exterior of the cylinder 19 is exteriorly threaded at 21. The lower portion of the cylinder 19 simulates a key-hole slot. The upper part of the key hole slot comprises a pair of diametrically opposite openings 22 whose centers are on a line at right angles to the longitudinal axis of the cylinder 19. The openings 22 as shown are portions of a circle, and are greater than a semi-circle and less than a full circle. The lower portion of the cylinder 19 is cut away inwardly from its lower edge to the openings 22. The cut away portion of the cylinder 19 are the incline surfaces produced by the intersections of the lower end of the cylinder 19 by a pair of planes at an angle to the central vertical axis of the cylinder 19, with the intersections extending from the lower edge of cylinder 19 to the openings 22 through cylinder 19, and with the angle of

intersection of one plane being greater than the angle of intersection of the other plane to provide a pair of unequal length members 23 and 24 having incline surfaces 25 and 26. The lower tip portion of the longer member 24 is cut away to provide a straight edge 45. The member 23 has an opening 27 therethrough adapted to be in alignment and coincidence with the upper opening in the cylinder 19. A leaf type closure 28 has a cylindrical journal 29 integral with the upper edge thereof and extending therefrom. The journal 29 is of such dimensions that its length approximates and may be slightly less than the diameter of the outer surface of the cylinder 19 and its diameter approximates and is slightly less than the diameter of the openings 22 in the cylinder 19. The contour of the outer periphery of the leaf 28 is approximately that of the outer periphery of incline surface 25, so that when the leaf closure 28 is in one position against the incline surface of the member 25, the leaf 28 is contiguous with said surface throughout its entire length. Integral with said leaf 28 at the apex and thereof is a projecting lobe 30 extending therefrom. The surface 31 of the lobe 30 opposite the lower opening in cylinder 13 is inclined. The length of the lobe 30 is of such magnitude that when the leaf is in one extreme position, the lobe 30 may extend part way into the opening in the lower part of cylinder 13 and may be in the path of the medium which may flow through said opening into cylinder 13.

Demountably disposed in the cylinder 19 is a solid member 32 which may be semi-cylindrical or slightly greater than semi-cylindrical. A flange 32' is integral with said solid member and extends outwardly from only the curvilinear upper portion thereof. The diameter of the exterior surface of the solid member is equal to or very slightly less than the diameter of the inner surface of cylinder 19. The solid member has an elongated transverse arcuate opening 33 whose center is on the vertical central axis of the solid member. The lower part of the solid member 32 is a plane incline surface 34 extending upwardly outward from its lower edge to the opening 33. This incline surface 34 is essentially the surface produced by the intersection of the lower part of the solid member by a plane disposed at an angle to the vertical and passing through the lower edge of the solid member to the opening 33. The solid member has a transverse opening 35 therethrough of the same diameter as the opening 27 and adapted to be in registry and coincidence with the opening 27 when the members are assembled.

As above described and as shown in the drawings the novel valve and all of its parts are simple, the parts may be produced inexpensively, and the assembly of the valve and its repair, if and when required, are extremely simple tasks which may be carried out even by unskilled workmen.

The novel valve assembly shown comprises a plurality of demountable parts which may be quickly assembled in the following manner. The conduits 16 and 17 may be readily demountably connected to the upper and lower openings in the cylinder 13 by a mere turning operation and these conduits which are preferably identical in all respects are interchangeable to keep to a minimum the time, effort and skill required to properly couple the conduits to the cylinder 13. The solid member 32 may be demountably coupled with the sleeve 19 by sliding the solid member therein and adjusting the flange 32' with respect

to the flange 20 until the opening 36 in the flange 32 is in registry with the threaded opening 37 through the flange 20. The flange 32' of the same diameter as flange 20 will be flush there against and the lower portion of the solid member is so disposed that its surface 34 is flush with the surface 26 of the portion 45, the openings 27 and 35 are in registry and coincidental with each other, and the arcuate slot or groove 33 is in registry and coincidental with the openings 22. The leaf closure 28 may be demountably connected to the sleeve 18 and the solid member by sliding the journal 29 through one opening 22, into the arcuate slot 33 and into the other opening 22. The so mounted leaf 28 is freely suspended in the bearing consisting of the openings 22 and the slot 33 and is free to swing either way on the journal 29. The outer ends of the journal 29 are flush with or slightly within the outer surface of sleeve 18. This sub-assembly may be demountably connected to the sleeve 13 by merely inserting through the top of cylinder 13, the sub-assembly and rotating one with respect to the other to make threaded engagement between the threaded portions 21 and 14. When the sub-assembly advances so the extreme lower face of flange 20 will be located close to the upper face of cylinder 13 and the openings 36 and 37 will be in alignment with a corresponding and short opening 38 in the cylinder 13. When the parts are so coupled, the extreme lower edge of the member 23 will be disposed above the lower opening in the cylinder 13, and the extreme lower edge of the member 24 will be disposed below the upper opening in the cylinder 13, the openings 35 and 27 will be in registry with the upper opening in cylinder 13, and the closure 28 will be freely suspended in the bearings 22 and 33. A threaded stud bolt 39 may be inserted through the opening 36 and make threaded engagement with the threaded opening 37 and extend into the opening 38 to assure perfect alignment and relationship of parts at all times. The relative position of parts may be visually ascertained by looking upwardly through the bottom of the cylinder 13. The bottom of the cylinder 13 may be capped by a threaded plug 40 having a flange 41 extending outwardly therefrom and being of the same external diameter as the cylinder 13. A square or other shaped boss 42 is integral with the plug 40 and extends outwardly therefrom and is used as a wrench grip device for tightening the plug in the threaded section 15 of cylinder 13. The device as above described is shown in vertical cross section in Figure 2.

The valve may be placed in the compressed air line 11 by disposing the valve vertically, with the head of bolt 39 uppermost, and threadedly securing sections of the line 11 to the conduits 16 and 17 with the conduit 16 being the air inlet side and 17 being the outlet side of the valve. With no air passing through the valve, the parts of the valve are in the position shown in Figure 2, with the closure 28 being freely suspended and disposed substantially vertically. In order to start the engine 10, compressed air is delivered to the cylinder of engine 10 from air under pressure in tank (not shown) by opening the control valve 12, whereupon the air under pressure passes through one leg of conduit 11, through valve 12, into conduit 16, through the check and relief valve, through the conduit 17, other leg of conduit 11 and thence to cylinders of engine 10. As the air passes into the cylinder 13 from the con-

duit 16, it forces the closure 28 to swing in the bearing 22 and 33 to the positions shown in Figures 6 and 7. When the closure 28 is in this position, the opening 43, which is slightly less than semi-cylindrical and determined by the inner plane surface of the solid member and the inner surface of cylinder 19 is now separated from the lower part of the hollow cylinder 13 with which it communicated. Further, the closure 28 is forced against the surface 25 of member 23 so that the surface 25 is contiguous with the closure 28 throughout its length to prevent the air under pressure from passing up through opening 43. In this position, the lobe 30 is disposed in the outlet opening 17 through which passes the air under pressure to the other leg of conduit 11. In the event of engine backfire the force of the gases traveling from the engine 10 through one leg of conduit 11 to the normally outlet conduit 17 to cylinder 13, first impinges against the lobe 30 to swing the closure 28 counter-clockwise and then acts against the entire face of the closure 28 to force said closure in the position shown in Figures 8 and 9 whereupon these gases pass upwardly outward through the opening 43 into the atmosphere. When in this position, the closure 28 is forced against the inner flat face 34 to close off completely the opening 35 whereupon no compressed air flows into cylinder 13, and the gases from engine 10 flow upwardly out of the cylinder 13 through opening 43. When the force of the backfire reaches a predetermined critical minimum pressure, the compressed air automatically forces the closure 28 back to its position as shown in Figures 6 and 7, and the compressed air is again fed into the cylinder 10.

When the compressed air is cut off from the engine by closing valve 12, the closure 28 is in the position shown in Figure 2 and in the event of back fire, the closure 28 is forced against the flat face 34 whereupon the gases due to back fire pass out of opening 43.

Although the invention has been described in detail, this is not by way of limitation, but by way of illustration and is not to be limited thereby.

I claim:

1. A valve comprising a cylindrical hollow body having one end open and a pair of side openings therein spaced about one hundred and eighty degrees apart, one of said openings being located higher than the other, a hollow sleeve demountable located in said open end and having a pair of oppositely disposed key-hole simulating slots therein defining a pair of legs, said legs being of unequal lengths, the longer leg having an opening therein disposed adjacent to and in alignment with the higher opening, means located in said sleeve to block a portion of said sleeve, a closure carried by the key hole slots of said sleeve and adapted in one position thereof to close the open portion of the sleeve and in another position to close the opening of the longer leg, an extension carried by said closure, said extension arranged to be disposed in the path of back-flow through the lower side opening of the hollow body.

2. A valve comprising a cylindrical hollow body having one end open and a pair of side openings therein spaced about one hundred and eighty degrees apart, one of said openings being located higher than the other, a hollow sleeve demountable carried by said body and located therein, said sleeve having a pair of oppositely disposed key-hole simulating slots extending through the lower end thereof and defining a pair of legs of unequal length, the longer of the two legs having an opening therein adjacent to and in alignment with the higher opening in said body and the other terminating above the other opening in said body, a demountable blocking means located in said sleeve and defining an elongated passage-way communicating with the outer atmosphere, said means having an opening therein opposite and in alignment with said higher opening, a closure, carried demountably by the keyhole slots of said sleeve, an extension carried by said closure and arranged to be actuated by back-flow to force said closure to one position to block off the opening in said means.
3. A valve comprising a body having a plurality of horizontal openings therein, one of said openings normally being an inlet and the other being an outlet, said body having a back flow opening therein disposed vertically and extending through one extremity of said body, a closure pivotally mounted in said body and constructed and arranged to be swung to block the back flow opening by the force of fluid as it flows from the inlet, through the body and the outlet, means secured to said closure and located in alignment with said outlet when said closure is in said back flow opening blocking position, whereby said means is actuated by back flow to swing said closure to block said inlet whereupon the back flow travels through the outlet, said body and through the back flow opening.
4. A valve comprising an open ended hollow cylinder having a pair of side openings therein spaced about one hundred and eighty degrees apart, one of said side openings located higher than the other, a hollow cylindrical open ended sleeve disposed in said cylinder, a flange secured to said sleeve and disposed adjacent the upper extremity of said cylinder, said sleeve and cylinder being demountably connected to each other, the lower end of said sleeve having a pair of oppositely disposed key hole slots therein defining a pair of legs, one of said legs being longer than the other, the longer leg having an opening therein opposite and in register with the higher side opening, the other leg terminating above the other side opening, blocking means located in said sleeve and demountably secured to said cylinder, said means having an opening therein opposite and in alignment with the higher side opening and the opening in the longer leg, a closure demountably carried by the key-hole slots of said sleeve, and demountable means closing the lower end of said cylinder.
